UNITED STATES PATENT OFFICE.

MARCEL VANDAL, OF PARIS, FRANCE.

COLORING-MACHINE FOR MOVING-PICTURE FILMS.

1,226,282.

Specification of Letters Patent.

Patented May 15, 1917.

Application filed June 7, 1912. Serial No. 702,331.

To all whom it may concern:

Be it known that I, MARCEL VANDAL, a citizen of the Republic of France, residing at 8 Rue Saint-Augustin, Paris, in the Republic of France, engineer, have invented certain new and useful Improvements in Coloring-Machines for Moving-Picture Films, of which the following is a specification.

This invention relates to a coloring machine for moving-picture films, in which the color is applied, in a well-known manner, by means of brushes and of openings in a positive film, the contours of such openings corresponding with those of the parts to be 15 colored.

My invention has been provided for the purpose of doing entirely away with hand-work in the application of the color, of giving great regularity to the coloring, and of 20 turning out a very great deal of work.

Among the difficulties heretofore found in the use of such machines, the greatest ones are those owing to the great exactitude required for the position of the negative film 25 on the picture film to be colored and the great uniformity required in the coloring without leaving any dribble or the least white spot, however small the said openings and however fast the machine may be running, such difficulties having not been overcome in a satisfactory manner in similar machines contemplated heretofore.

On the other hand, the said difficulties are quite eliminated in the machine according to 35 this invention by the use of a device for carrying forward the picture film and keeping the same in register with its positive film, such device compensating for the slight and unavoidable irregularities of their perforations; of a system of brushes having particular movements which do away with white spots and dribbles whatever the speed 40 may be; and of an inking device with the brushes.

45 The essential arrangements of my machine will now be described, by way of example, with reference to the accompanying drawings:—

Figure 1 is a side elevation of the machine, some parts being removed or broken away for the purpose of greater clearness,

Fig. 2 is a bottom plan view of a swinging plate carrying the system of brushes.

Fig. 3 is a front elevation of the machine; 55 and

Fig. 4 shows the details of a guiding disk. The main frame 1 of the machine supports two drums 2 and 3 located at the ends of a horizontal table 4 on which the film 5 to be colored and the film 6 provided with openings are passed. The latter are perforated as usual and are enabled to mesh with the teeth provided on the drums 2 and 3, in contact with which the film is maintained by pressure rollers 7 and 8, the springs of which 60 are not shown.

The drum 2 is loosely mounted; it is kept 65 yieldingly in contact with the film by means of a leather buffer 9 bearing against one of its ends; such buffer is carried by a flat 70 spring 10, the tension of which can be adjusted by means of a screw 11. On the other hand, the drum 3 is actuated mechanically; its spindle or shaft carries a worm wheel 12, (Fig. 1), meshing with a worm 13 having a 75 continuous rotary motion. So the drum 3 acts as a carrier and the drum 2 acts as a stretcher of the film; this allows of keeping the film under tension in an adjustable manner during its passage on the table 4. 80

Underneath the table are located two studs 14 on each of which are loosely mounted two toothed disks 15 designed to insure the proper position of the open-work film and the color film the one with respect to the 85 other. The teeth of the disks 15 pass freely into openings of the table and mesh with the perforations of both the films. Such teeth are of a special shape, shown in Fig. 4; the section of each tooth, perpendicularly to the 90 axis of the disk, is ogive; in the plane passing through the axis, the section is rectangular, the angles at the apex being rounded off and the width being equal to that of the perforations of the film; the base of the 95 tooth is of the same shape as the said perforations, that is to say the form of a circle two opposite segments of which have been removed. The result of such peculiar shape is that in coming into engagement with the 100 teeth of the disks, those portions of the two films comprised between the said disks are centered exactly on one another, while such disks, by reason of their freedom, are enabled to move independently of one another 105 in lending themselves to the slight variations of the space between the perforations both as to width and length, and particularly to the defects of the symmetry of their positions with respect to the axis of the strips. 110

It is to be noted that in such a system the film 5 carries forward the loosely mounted disks and the latter, in turn, carry forward the open-work film causing the latter to place itself exactly on the top of the color film at the four points where the teeth of the disks mesh with the perforations in the films and, consequently, in the whole of the portion comprised between such points.

10 The differences of the space between the holes in the longitudinal direction are generally of no importance and are compensated for by the tension under which both the films are continuously put between the 15 disks 15.

In the direction of the width, the differences are greater; easily changeable disks will be employed and of which the teeth will have a width equal to half the difference between the largest and smallest distance between the edges of the holes (largest for the open-work film and smallest for the film to be colored); the errors will thus be reduced to a minimum and equally divided between 25 the two sides.

In any case, the guiding-mark of the pictures will be exactly at the center of the latter, which is the main point.

The edges of both the films pass under 30 metal rulers 16 which hold the same lightly on the table 4.

The coloring is effected by means of two brushes 17 and 18 upright and extending perpendicularly to the movement of the 35 strips 5 and 6, and of two inking tapes 19 and 20 which move parallel to such strips on the lateral extensions of the table 4.

The brushes receive circular movements in inverse directions so that the distance between their longitudinal axes remain always 40 the same. Such motion can be very easily obtained as shown in the drawing. Each brush is secured to a metal plate 22 provided with a central boss 23 which in turn 45 is secured to a rod 24 parallel to the brush; on one end of each rod 24 is secured a block 25 which is provided with a hole for the passage of the other rod; both the brushes are thus guided parallel to each other and 50 are held always at the same distance from one another. Each of the blocks is pivoted to a wrist pin 26 and the pins 26 are carried by two gear wheels 27 mounted on a plate 28; both the gear wheels are connected 55 together by two intermediate pinions 29 so that they can only revolve in inverse directions and always at the same speeds. In the embodiment shown, the wrist pins 26 are placed symmetrically with respect to the 60 perpendicular x-x drawn from the line of the centers of the wheels at the middle on such line. All the points of the brushes 17 and 18 and of all the members 22, 23, 24, 25, which are connected therewith, are thus 65 caused to describe circles equal to the circles

symmetrically directed by the pins 26 and the brushes are always kept in the same direction. However, the invention is not limited to such peculiar motion; for instance, one of the pins 26 may be made movable to make the brushes swing while being circularly revolved so that the different points of the brushes will describe irregular curves, of 8 or other suitable shapes.

One of the wheels 27 is operated by means of a pulley 30 driven by a round belt 31 which also drives the worm 13 in passing around a pulley 32 coöperating with the said worm, the belt being preferably operated by an electric motor located underneath the machine and passes around the rollers 33 and 34, and the pulleys 30 and 32, as shown in the drawings. As the plate 28 carrying the brushes is hinged on the spindle of the rollers 34, the control is so arranged that, by merely raising the said plate, the strips 5 and 6 can be uncovered, the brushes can be inspected, and the belt can be slackened, thus stopping the machine at once.

When the plate 28 is lowered and held in such position by a spring latch (not shown) which acts on the member 35, the brushes are pressed on to the openings of the positive film and on to the inking tapes 19 and 20. By reason of their circular motion, the said brushes take the color from the tapes and discharge the same on to the film to be colored through the said openings. The speed of the rotation of the wheels 27 is such that the brushes make several circular movements, four for instance, while the drum 3 advances the film to the height of a picture; whereby as the film is being moved the direction of the passage of the bristles of the brush at a determined point of such film changes continuously and such direction is suddenly reversed several times by reason of the inverse movements of the two brushes. Such repeated changes of direction have the effect of spreading the color into all the 100 openings of the positive film, however irregular may be the contours of such openings. Again, the continual reciprocation of the brushes on both the lateral tapes and on the open-work film has the effect of feeding 105 the color equally on both sides and of securing the absolute uniformity of the tints deposited. It is to be noted that when the half of a brush passes on to the picture, the other half is taking the color from one of the 110 tapes, and that then the first half takes the color from the other tape while the second half will pass in turn on to the picture; the other brush which moves in the inverse direction operates in the same manner. The 115 large number of alternative passages on to the strips and tapes allows of charging and discharging each time only a very small amount of color, which tends to avoid drippings. The latter are also avoided on ac- 120

count of the tension of the strips, the continuous pressure on the brushes and of the exact register of the open-work film with the film to be colored by means of the disks 15, 5 which coöperate in maintaining the edges of the openings always on the film to be colored. The color tapes 19 and 20 pass around the drums 36 located at both sides of the parts 21 of the table and around the drums 37 10 which dip into color containers 38; they are stretched by stretching rollers 39. The drums 37 are secured on the same shaft and driven by a ratchet wheel 40 and a lever having a pawl 41 which is connected by a link 42 15 with a rocker arm 43; the latter is operated by means of an arm 44 and a wheel 45 having lateral pins which is secured to the shaft of the wheel 12 and the drum 3. A spring 46, acting for instance on the link 42, holds the 20 arm 44, by means of an inclined plane 47, against the pins of the wheel 45. During the rotation of the latter the pins push and leave successively the arm 44 so that the pawl lever 41 moves back and forth and advances the drums 37 and hence the tapes 19 25 and 20 intermittently. Such forward movement can be adjusted by modifying the swing of the arm 44, as for instance by means of a spiral way, an abutting screw, or 30 the like; the amount of color fed to the brushes can thus be regulated according to requirements.

It must be understood that the above described embodiment is only given by way of example and that without departing from the invention all the structural arrangements may be modified, for instance, the number of the brushes may be varied, and the driving mechanism may be replaced by 40 any other mechanism adapted to give the same the desired circular motions with or without any transverse swinging, as also the device for advancing the color tapes which may be replaced by any equivalent device.

45 Claims:

1. A coloring machine for films comprising a table, means for guiding in a straight line on the said table a film and an open-work coloring film, the latter film being on 50 the top of the former one, inking or coloring tapes arranged parallel to the path of the film, on both sides of such path, brushes located above the table, and so arranged as to 55 convey the colors from the tapes to the open-work film, and means whereby to im-

part to the brushes both opposite reciprocatory movements and a general circular movement in the plane parallel to the table.

2. In a coloring machine for films, the film to be colored and the openwork film 60 having the usual perforations, the combination of a table, a pair of spaced drums between which the films are extended over the table, two axes parallel to the table between the said drums, four toothed disks 65 mounted in pairs on the said axes and of which the teeth are adapted to engage in the perforations of the films, all of said disks being loosely mounted in their said axes so as to slide and rotate upon their 70 said axes separate from one another.

3. In a coloring machine for films, the combination of a table having guiding means for guiding a film and an open-work film, the latter film on the top of the former 75 one, a main frame supporting such table, a plate hinged on the table, rotary plates mounted on the said plate, movable brushes carried by such plates, a grooved pulley mounted on the said plate and adapted to 80 revolve or turn such plates, grooved rollers mounted on the main frame, and an endless cable passing around the said rollers and around the pulley to drive the pulley, the position of the pulley and of the rollers 85 being such that the cable is taut when the plate is horizontal and slackened when the latter is upright.

4. In a coloring machine for films, the combination of means for supporting and 90 moving the films to be colored, an endless inking or coloring tape, drums around which the said tape passes, a color container in which one of the said drums is partly submerged, means connected to the means 95 for moving the films and arranged for imparting a forward movement to the tape, color brushes so arranged as to take the color from the tape and apply it to the films, and means whereby to impart to the brushes 100 both opposite reciprocatory movements and a general circular movement.

In testimony that I claim the foregoing as my invention I have signed my name in presence of two subscribing witnesses.

MARCEL VANDAL.
